UNITED STATES PATENT OFFICE.

WILLIAM HENRY TOWNE HOLDEN, OF NEW YORK, N. Y., ASSIGNOR TO WESTINGHOUSE LAMP COMPANY, A CORPORATION OF PENNSYLVANIA.

HIGH-TENSION DEVICE.

Application filed January 2, 1922. Serial No. 526,455.

My invention relates to electrical devices employing high potentials, and more particularly it relates to hot-cathode apparatus, such as X-ray tubes and rectifiers.

5 An object of my invention is to provide a device of the character indicated which will be strong and durable.

Another object of my invention is to provide a high-potential device in which the 10 lines of force of the electrical field are prevented from passing through the walls of the envelope.

Another object of my invention is to provide a device of the character indicated in 15 which flare-backs, corona and flash-over are obviated.

Other objects will be apparent from a reading of the following description.

Heretofore in the construction of high-tension tubes, particularly those employing hot cathodes, such as X-ray tubes and rectifiers, no provision was made for preventing the lines of force of the electrical field surrounding the electrodes within the envelopes 20 of such devices from passing through the walls thereof. Apparently, because of the passage of the lines of force through a dielectric body at an angle other than 90° and of the concentration of such lines of 25 force when effecting such passage, and, furthermore, because of the surging of these lines back and forth under the influence of an alternating current, the dielectric is subjected to stresses which, when the dielectric 30 is of glass, results in the breaking-down or puncture thereof, with consequent failure of the device. The rupture of the dielectric usually occurs near the seals and at the sharp angle formed at the intersection of the intermediate portion of the tube and the tubular 35 extensions projecting from opposite sides of the tube. Inasmuch as these devices are very expensive, it is desirable to prevent such breakage. Another disadvantage which is 40 present in X-ray and rectifier tubes, as at present constructed, is that occasional electrical discharges, known as corona and flash-over, occur at sharp projections and along the walls of the tube, especially adjacent the 45 points where the electrodes pass through the walls. When such discharges occur they follow the walls of the tube and cause it to be unduly heated, a condition which results in the fracture of the envelope. In addition 50 to the foregoing disadvantages of high-tension

tubes as heretofore constructed, it is also noted that gases are liberated from the electrodes, even after the greatest care has been exercised in eliminating such gases. 60 This liberation of gas is the result of discharges, or flare-backs, from the electrodes toward the point where the electrodes emerge from the glass stem. Such discharges heat up the stem, puncture it and expose portions of the electrodes which have 65 not been treated to remove the occluded gases.

The foregoing disadvantages have been obviated by the provision of hollow conductors about the neck portions of these devices. 70 These conductors are designed to divert the lines of force representing the electrostatic field so that they conform to the contour of the envelope, and, at the same time, remove the field from the vicinity of 75 the seal portion of the envelope. In addition to securing the foregoing advantages, the hollow conductors also function to prevent corona and flash-over and also assist in dissipating the heat resulting from the 80 energy liberated at the electrodes of the tube. By properly placing a shield within the envelope, the objectionable consequences of the flare-back discharges are obviated.

An embodiment of the invention is illus- 85 trated in the annexed drawings, in which,

Fig. 1 is an elevational view of a well-known form of an X-ray tube showing the approximate positions of the lines of force representing the electrostatic field surround- 90 ing the electrodes therein;

Fig. 2 is an elevational view of the device illustrated in Fig. 1, showing the metallic cover or shield applied thereto and the altered position of the lines of force repre- 95 senting the electrostatic field;

Figs. 3 and 4 illustrate the position of the external metallic covers with respect to bulbs having ellipsoidal and cylindrical surfaces, respectively; and 100

Fig. 5 shows an interior shield formed of mesh material.

The invention comprises a pair of hollow metallic shields of conductive material positioned exteriorly of the bulb and adjacent the ends thereof at the point where the lead-in wires for the electrodes, or the electrodes, pass through the walls, which part is usually termed the seal of the tube. These shields are conductively connected to the 105 110

electrodes, or may form parts thereof, and completely surround the same, as well as the seal portion of the tube. A surface of the shields intersects the surface of the envelope at an angle of approximately 90°. Within the envelope and preferably surrounding each of the electrodes, is a hollow conical shield which has a portion of its surface inclined at an angle of 90° to the 10 surface of the envelope, which surface forms a continuation of the angular surface of the outer shield. The inner shield is preferably made of open-mesh material in order to facilitate its being positioned within the 15 tube.

Referring now to the drawings, and particularly to Fig. 1, a conventional X-ray tube is illustrated as composed of an envelope made of a transparent material, such 20 as glass, having an intermediate portion or glass bulb 6 and a pair of oppositely extending tubular portions 7, usually termed the neck portions of the tube. The contour of the envelope varies, but usually the curvature of the intermediate portion 6 is spherical, as in Fig. 2, although this section may have an ellipsoidal form 8 or a cylindrical form 9, such as illustrated in Figs. 3 and 4, respectively. Within the neck portions of 25 the device are mounted, in any desired manner, the lead-in wires 11, which may be connected to the electrodes 12 or form a part thereof. High potentials are impressed 30 upon the electrodes during the operation of 35 the device.

In the devices heretofore constructed, due 40 to the sharp curve 13 at the juncture of the intermediate portion and the neck portion of the tube, the lines of force representing the 45 field surrounding the electrodes pass through the walls of the envelope at an angle other than 90°. In Fig. 1 is illustrated a conventional form of X-ray tube showing approximately the arrangement of the lines of force representing the electrostatic field. It 50 will be apparent from this view that these lines of force enter the walls of the envelope at an acute angle and in passing therethrough are somewhat concentrated, particularly at the juncture point previously 55 mentioned. Because of this concentration, and the angular passage of the force line through the envelope, together with the 60 constant surging of these lines back and forth under the action of the alternating current, the dielectric substance is subjected to considerable stresses. These stresses cause the dielectric material to become strained and eventually cause its dissociation, with resultant breakage of the device, particularly at the neck portions.

In order to overcome or prevent such breakage, I propose to remove the electrostatic field from the region of the neck portion of the device by the provision of a

pair of properly formed and proportioned hollow conductors about that section of the device. In Fig. 2, a pair of shields 14, formed of a suitable conductive material, which, at the same time, will also serve to 70 radiate the heat readily, are placed in a concentric position about the seal portions of the tube. Preferably, the shields are in the form of hollow shells which are adapted to completely enclose, and be spaced from the 75 neck portions of the device. The shells may have their rear portions 15 connected to the electrodes while their forward walls 16 are arranged at an angle of approximately 90° with respect to the surface of the intermediate portion or bulb of the envelope. This 80 angular arrangement is essential because of the contour of the electrostatic field which it is desired to secure, since the lines of force emanate at an angle of 90° from 85 the surface of the charged body and gradually curve toward the body of different potential. Where the contour of the tube is different from that illustrated in Figs. 1 and 2 and is such as shown in Figs. 3 and 90 4, the right angular arrangement of the surface of the walls 16 will still obtain. The conductive shields may be secured in any desired manner to the electrodes, and, where 95 the tube employs a radiator 17, (Fig. 1) one of the shields may be fastened thereto. It is to be appreciated that these shields, being relatively large, also assist in dissipating the heat resulting from the energy liberated at 100 the electrodes of the tube.

By completely enveloping the neck portions of the tube, the electrostatic discharges, known as corona and flash-over, are prevented. This results from the well-known property of a hollow conductor, in which electrostatic fields cannot exist but are confined wholly to the exterior thereof.

To aid in flexing the lines of force to lie in lines substantially parallel to the walls of the envelope, the portion of the electrodes disposed within the tube may be provided with a pair of conducting members which are preferably formed of mesh material. These conductors are affixed to, or supported by, the electrodes or lead-in wires, or in any other convenient manner, but should be in conductive relationship with the source of potential. These interior shields may form parts of the electrodes, or the electrodes may be so designed as to produce the desired effect. A portion of the surface of each of the interior shields is preferably arranged at an angle of 90° to the surface of the intermediate portions of the tube and should also form a continuation of the correspondingly arranged angular surface of the exterior shield.

It is obvious that these interior shields 18 may be formed of solid material, but it is preferable to construct them of wire mate 130

rial, such as indicated in Fig. 5, wherein a plurality of fine wires 19 may be fastened to collars 21 and clamped to the electrode 12. The ends of the wires are held in spaced relationship by rings or loops 22, which may be secured in place after insertion of the shield within the envelope. Whether the interior shields are formed of solid or mesh material, the occluded gases should be treated out before or after they are placed within the envelope.

In practice, it may be preferable to omit the interior shields (see Figs. 3 and 4), in which event only the lines of force exteriorly of the envelope will be made to conform to the contour thereof. Inasmuch as the hollow conductors prevent any field being formed within the seal portion of the device, it is obvious that such lines will not be present anywhere within the interior of the envelope embraced by the hollow exterior shields. As these shields extend to a point adjacent the inner ends of the electrodes, the lines of force emanating from the electrodes will be confined to the intermediate portion of the device and thus be removed from that section of the device where the breakage ordinarily occurs.

With the shields arranged as indicated in Fig. 2, the lines of force representing the electrical field will be caused approximately to parallel the walls of the intermediate portions of the tube. In this way, the passage of the high potential through the dielectric forming the envelope of the tube is prevented and the breakage or puncturing of the tube obviated. At the same time, the electrical field is removed from the neck portion of the envelope and the phenomena known as corona and flash-over obviated. The interior shields assist in conforming the lines of force to the walls of the envelope and also prevent "flare-back" discharges occurring within the tube as, obviously, the discharges, if any, will strike the shield and thus be prevented from attacking the stems.

Many modifications may suggest themselves to those skilled in the art, but such as come within the scope of the appended claims may be considered as part of my invention.

What is claimed is:

1. The combination with two conducting members of unlike electrical potentials disposed within a closed envelope, of means for preventing the lines of force representing the electrical field from passing through the major portion of the walls of said envelope.

2. The combination with two conducting members of unlike electrical potentials disposed within a closed envelope, of means exteriorly of said envelope for preventing the lines of force representing the electrical field surrounding said members from pass-

ing through the major portion of the walls of said envelope.

3. The combination with two conducting members of unlike electrical potentials disposed within a closed envelope, of cooperating means on each end of said envelope exteriorly thereof for preventing the lines of force representing the electrical field surrounding said members from passing through a portion of the walls of said envelope.

4. The combination with two conducting members of unlike electrical potentials disposed within a closed envelope, of means on each side of said envelope and in contact with said members for causing the lines of force representing the electrical field surrounding said members to substantially conform to the contour of said envelope.

5. The combination with two conductive members of unlike electrical potentials disposed within a closed container having intermediate portions and a plurality of oppositely extending tubular portions, of conductive means positioned adjacent said conductive members for causing the lines of force representing the electric field to conform to the contour of the envelope.

6. The combination with two conducting members of unlike electrical potentials disposed within a closed envelope having a bulb and two oppositely disposed tubular sections of a pair of shields of conducting material of unlike electrical potentials disposed about said tubular sections and cooperating with each other to prevent the lines of force representing the electric field from passing through the walls of the envelope.

7. The combination with two conducting members operable at different potentials disposed within a closed envelope, of a plurality of hollow conductors of greater diameter than the envelope connected to said conducting members, said hollow conductors enclosing said conducting members and disposed exteriorly of said envelope, whereby corona and flash-overs from those portions of the envelope within said conductor are obviated.

8. The combination with two conducting members operable at different potentials disposed within a closed envelope, of a plurality of hollow conductors of greater diameter than the envelope connected to said conducting members, at least one of said hollow conductors enclosing that portion of said envelope through which one of said conducting members passes, whereby electrical discharges from said portion are prevented.

9. In a high potential discharge tube, means for preventing the lines of force representing the electrical field from passing through the walls of a portion of said tube comprising a pair of hollow conductors as-

1. 60 sociated with the opposite ends of said tube having a portion of their surface arranged at right angles thereto.
2. 65 10. A hot-cathode device comprising an enclosing envelope, a plurality of spaced-apart conducting members of unlike potentials and means for preventing the lines of force from passing through the walls of a portion of said envelope comprising a pair of hollow conductors associated with each end of said envelope extending inwardly towards each other with their adjacent faces opposed and arranged approximately at right angles to the surface of the envelope.
3. 70 15. 11. A discharge device comprising an envelope having a pair of electrodes therein and a conductor associated with each of said electrodes having a portion of its surface arranged substantially at an angle of 90° to the surface of the envelope to cause the lines of force representing the electrical field to assume a position substantially parallel to the walls of the envelope.
4. 75 20. 12. An X-ray device comprising an evacuated envelope, a pair of spaced-apart electrodes of unlike electrical potentials, a pair of hollow conical conducting shields concentric to each electrode and connected thereto and a pair of hollow conductive shields exterior to said tube and enclosing and connected to said electrodes, said shields having at least a portion thereof disposed at right angles to the walls of said tube.
5. 80 25. 13. An X-ray device comprising an evacuated envelope, a pair of spaced-apart electrodes of unlike electrical potentials, a pair of conductive shields within said envelope, said shields being connected to said electrodes and having at least a portion thereof disposed at right angles to said envelope.
6. 85 30. 14. An X-ray device comprising an evacuated envelope, a pair of spaced-apart electrodes of unlike electrical potentials, a pair of shields composed of wire disposed within said envelope, said shields being connected to said electrodes and having at least a portion thereof disposed at right angles to said envelope.
7. 90 35. 15. In a hot-cathode device, means disposed about the neck portions thereof and spaced therefrom for removing the electrical field from that portion of the device.
8. 95 40. 16. A hot-cathode device comprising a sealed envelope having a spherical intermediate portion and oppositely extending tubular portions, an electrode sealed in each tubular portion and projecting within said in- termediate portion and a hollow metallic member enclosing each of said tubular portions and a part of said spherical portion of the envelope, said hollow members being connected to said electrodes.
9. 100 45. 17. The combination with two conducting members of unlike electrical potentials disposed within a closed envelope, of a plurality of hollow conductors of considerable surface area disposed exteriorly of said envelope in electrical connection with said conducting members and enclosing the same so that heat resulting from the energy liberated at the electrodes of the tube may be dissipated and the electrostatic field removed from a position adjacent said conducting members.
10. 105 50. 18. The combination with two conducting members of unlike electrical potentials disposed within a closed envelope, of a pair of hollow shields surrounding and completely enclosing the ends of said envelope adjacent said electrodes, each of said shields being of large surface area and having at least a portion thereof arranged at right angles to said envelope so that the lines of force representing the electric field will be made to conform to the contour of said envelope and the heat generated will be dissipated.
11. 110 55. 19. An X-ray device comprising an evacuated envelope composed of two opposed tubular neck portions and an intermediate portion of uniform contour connecting said neck portions, a pair of spaced-apart electrodes operable at unlike electric potentials within said tubular portions and having their free extremities within said intermediate portion, and a hollow shield spaced from said neck portion and concentrically arranged with respect to each of said electrodes adjacent the extremities thereof and connected thereto.
12. 115 60. 20. An X-ray device comprising an evacuated envelope composed of a bulb and oppositely extending arms connected thereto, a plurality of electrodes, one of which is sealed within each arm and has its extremity within said bulb, a plurality of spaced-apart hollow conductive shields completely enclosing said arms and connected to said electrodes, a hollow shield concentrically disposed adjacent the inner end of each of said electrodes and connected thereto, each of said shields having at least a portion thereof disposed at right angles to the surface of said bulb.
13. 120 65. In testimony whereof, I have hereunto subscribed my name this 30 day of December, 1921.

WILLIAM HENRY TOWNE HOLDEN.
